His Attorney

UNITED STATES PATENT OFFICE.

LAURICE L. LOCKROW, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

ELECTRICAL APPARATUS.

Application filed September 14, 1926. Serial No. 135,398.

My invention relates to electrical apparatus, and particularly to apparatus of the type comprising a load supplied with energy from a source of pulsating current.

5 One object of my invention is the provision, in apparatus of the type described, of means for smoothing out the pulsations in the current supplied to the load.

I will describe one form of apparatus embodying my invention, and will then point out the novel features thereof in claims.

The accompanying drawing is a diagrammatic view illustrating one form of electrical apparatus embodying my invention.

15 Referring to the drawing, the apparatus comprises a source of pulsating current which is here shown as a rectifier R supplied with energy from the secondary S of a transformer T. The primary P of this 20 transformer is supplied with alternating current from a suitable source here shown as an alternator X.

The rectifier R comprises a plurality of asymmetrical units which may be of the 25 copper oxide type described and illustrated in an application for Letters Patent of the United States, Serial No. 1111, filed January 7, 1925, by Lars O. Grondahl for unidirectional current carrying devices. These 30 asymmetrical units offer considerably higher resistance to current flowing through them in one direction than to current flowing in the opposite direction. The direction of lesser resistance is indicated by the arrows.

35 The rectifier R supplies pulsating current to a load which is here illustrated as the filaments 5 and 12 of a plurality of electron tubes A¹, A², A³, and D¹, D² respectively, such as are used in radio receiving circuits. In 40 series with each filament 5 is a resistor 4, and connected in series with each filament 12 is a resistor 11. These filaments are connected across the terminals 14 and 15 of the rectifier R through two reactors 6 and 13.

45 During one half cycle, current is supplied from the secondary S of the transformer T, through wire 1, unit 10, reactor 6, multiple connected filaments 5 and resistors 4, wire 3, unit 9, and wire 8 back to the secondary S. Current is 50 also supplied during this half-cycle through the reactor 13, and filaments 12 and resistors 11 in multiple. During the opposite half-

7, reactor 6, filaments 5 and resistors 4 in 55 multiple, wire 3, unit 2 and wire 1 back to secondary S. During the second half cycle current is also supplied through the reactor 13, and filaments 12 and resistors 11 in multiple.

60 The current supplied from the rectifier R normally pulsates in a manner which would tend to produce disturbances in the plate current of the amplifier tubes A¹, A² and A³ and also in the plate current of detector tubes D¹ and D². In order to smooth out these pulsations the reactors 6 and 13 are provided. The reactor 6 which is associated with the 65 amplifier tubes A¹, A² and A³ has a low direct current resistance because these tubes require considerable current, but due to the 70 connections of the filaments 5 and the resistors 4 in multiple, the pulsations in the rectified current are smoothed out, the voltage induced in the reactor 6 when the current 75 is decreasing being in such direction as to oppose the decrease in current. The filaments 5 and resistors 4 being non-inductive, 80 cooperate with the reactor 6 to form a "ladder" filter which may be proportioned to oppose the passage of the alternating component of the rectified current. The reactor 13 co-operates with the detector tubes D¹ and D² in a similar manner but this reactor has a high ohmic resistance because the detector 85 tubes require much less current than the amplifier tubes. This reactor may be proportioned with respect to filaments 12 and resistors 11 to effectively smooth out the pulsations in the current supplied to the filaments 90 12. By suitably proportioning the reactors 6 and 13 the pulsations in the rectified current may be so reduced as to eliminate undesirable disturbances in the plate circuits of the detector tubes D¹ and D².

95 It will now be seen that I have provided a circuit which will reduce the disturbances in the plate circuits of electron tubes having their filaments supplied with alternating current by filtering out the undesirable components and that this circuit requires, for performing the filtering operation, very little extra apparatus over that which is normally required without the filter.

100 Although I have herein shown and described only one form of electrical apparatus embodying my invention, it is understood that various changes and modifications

may be made therein, within the scope of the appended claims, without departing from the spirit and scope of my invention.

Having thus described my invention, what I claim is:

1. In combination, a source of pulsating current a plurality of reactors in series with the source, a plurality of electron tubes having their filaments connected in multiple, and 10 a resistor in series with each filament and arranged to co-operate with the reactors to form a ladder filter.
2. In combination, a source of uni-directional pulsating current, a plurality of electron tubes having their filaments connected in multiple, a resistor in series with each filament, and a reactor in series with the source and co-operating with the resistors to form 15 a ladder filter.
3. In combination, a source of pulsating 20

current, a plurality of electron tube amplifiers having their filaments connected in multiple with one another across the source, a resistor in series with each filament, a low resistance reactor connected between the 25 source and the filaments of the amplifiers and co-operating with said filaments and resistors to form a ladder filter, a plurality of electron tube detectors also having their filaments connected in multiple with one another across the source, a resistor in series with each detector tube filament, and a high resistance reactor in series with the source and with the low resistance reactor and connected between the amplifier and detector 30 tubes and co-operating with each detector tube filament and its associated resistor to form a ladder filter.

In testimony whereof I affix my signature.

LAURICE L. LOCKROW.
